UNITED STATES PATENT OFFICE.

JOHN KEATS AND CHARLES H. KEATS, OF STAFFORD, ENGLAND.

SOLE-TRIMMER.

SPECIFICATION forming part of Letters Patent No. 437,857, dated October 7, 1890.

Application filed July 2, 1889. Serial No. 316,333. (No model.) Patented in England February 25, 1887, No. 2,968, and in France April 1, 1887, No. 182,583.

To all whom it may concern:

Be it known that we, JOHN KEATS and CHARLES HORATIO KEATS, both of 41 Gaol Road, Stafford, in the county of Stafford, England, have invented certain new and useful Improvements in Compound Cutters for Par-

ing the Soles of Boots and Shoes, (for which we have obtained English Letters Patent No. 2,968, dated February 25, 1887, and a French Brevet d'Invention No. 182,583, dated April 1, 1887,) of which the following is a specification.

The object of this invention is so to construct the compound rotary cutters of boot or shoe sole paring machines as, first, to obtain a uniform depth of cut from the profile or peripherical cutters, notwithstanding the wearing away of their cutting-edges, and, secondly, to provide for the adjustment relatively to the profile-cutters of the chamfering or face cutter to suit the work in hand whether the paring-machine be running or quiescent.

In the accompanying drawings the compound cutter is shown complete in side view at Figure 1, and in front view at Fig. 2; and Fig. 3 is a longitudinal section of the same, taken in the line 1 2 of Fig. 2. Fig. 4 shows in side view, and Figs. 5 and 6 in front and back views, the profile-cutter holder detached, its cutters being in place. Fig. 7 is a side view, and Figs. 8 and 9 front and back views, of the chamfering-cutter holder detached, its cutter being in place. Figs. 10 and 11 show, in longitudinal section and front view, a modified construction of the profile-cutter. Figs. 12 and 13 show detached and in front and edge views, the "bitting-cutter" or welt-plow, forming also a guide. Figs. 14 and 15 show, detached and in front and edge views, the rotary ventilator-guard for carrying the guiding bitting-cutter. Fig. 16 shows, in edge view, the bitting-cutter guide fitted to its guard in the position it occupies when operating on a boot-heel.

The compound cutter consists of three sets of cutting-edges—viz., one set for profile-cutting, one set for chamfering, and one set for bitting or removing the burr from the boot sole or welt near the upper and from the heel seat or rand.

A is the spindle of the paring-machine, upon

which is screwed the holder or block B for the profile-cutters b.

A' is a sleeve, which is free to slide over the profile-cutter holder B, for the purpose of adjusting the breadth of cut of the profile-cutters to suit the work in hand.

b b, Figs. 4 and 5, are the profile or peripherical cutters, which are segment-shaped from their front edge to their heel. These cutters, which form a group of six or more, are fitted in rabbets cut in the periphery of the cylindrical block B, so as to give them an eccentric set, and they are held in place by means of binding-screws. Screwed to the back of this block is a disk B', which receives the sleeve A', fitting it so as to allow of the sleeve sliding freely over the cutter-holder.

Cast in one with the block B is a hollow center-piece B², which is internally threaded to fit onto the spindle A of the paring-machine.

Drilled through the block B and disk B' at opposite sides of the center piece are holes, which form guides for two parallel guide-rods projecting rearward from a holder C, to which the chamfering-cutter D is attached. One such guide-rod, however, may suffice. These rods also pass through the closed end of the sleeve A', and by means of a binding-screw bearing against one of the rods the holder C is, when adjusted, made fast to the sleeve A.

The chamfering-cutter holder C consists of a ring turned to fit a recess made in the face of the holder B and slide freely therein.

The chamfering-cutter D is star-shaped, and its limbs form the cutting-blades. These blades will generally correspond in number with the profile-cutters, as shown in the drawings, and to receive these blades there are formed in the front edge of the sleeve A' a corresponding number of radial recesses a, their object being to provide for the adjustment of the sleeve relatively to the blades, and thereby to gage the depth of cut made by the blades.

It will be understood that the cutters b have a profile corresponding to the work to be done, and that the cutters are so mounted on their holder that their edges will stand out eccentrically or tangentially and sufficiently in rear

of the heel of the next adjacent cutter to leave ample room for the discharge of chips or shavings.

5 E, Figs. 12 and 13, is the biting or burr-removing cutter, which serves also as a guide for the work. This cutter, which consists of a ring of steel with inclined cutting-edges *e* punched up so as to leave the outer periphery of the ring unbroken, is carried by a guard *F*, 10 mounted loosely on the spindle *A*. This guard may be described as a hollow cone having arms for connecting it with its hub, such arms being helically disposed, for the purpose to be presently explained.

15 Keyed on the spindle *A*, Fig. 1, is a collar *A'*, against which the conical guard abuts, it being held in contact therewith by the adjusting of the cutter-holder on its spindle until the cutters *b* bear against the ring *E*. The 20 cutting-edges *e* of the ring *E* project into the spaces between the profile-cutters *b*, and as the spindle *A* is rotated the ring *E* and conical guard *F* will be caused to rotate with the cutter-holder *B*.

25 The chamfering-cutter *D* is conveniently stamped out of one piece of steel, there being, say, six cutting-blades, which enter the six openings between the heel and cutting-edge of the adjacent profile-cutters *b* of the holder *B*. These cutting-blades are preferably made tangential and are bent rearward to enable them to make an inclined cut in their revolution, as illustrated in Figs. 3 and 7.

30 The holder of the cutter *D* is attached to the sleeve *A'*, as above explained, for the purpose of enabling the sleeve to slide the chamfering-blades between the heel and edge of the adjacent profile-cutters to suit the various thicknesses of the work in hand. Thus in 35 the dotted position of Fig. 1 the cutter *D* is shown as advanced to chamfer the waist of a boot, whereas in the drawn position of the same figure it is represented in a position for chamfering the sole. This movement is effected by giving an endwise motion to the sleeve *A'*. For this purpose an annular groove *a'* is turned in the sleeve *A'* to receive a fork *G*, carried by an adjusting-screw *G'*. This screw is supported in lugs cast with the bearing 40 in which the spindle *A* is mounted. Adjusting-nuts *g* serve to advance and draw back the screw *G'*, and thereby, through the fork *G*, shift the sleeve *A'* and the chamfering-cutter *D* relatively to the profile-cutters. By 45 this means, therefore, the cutter *D* may be brought to act upon work of various thicknesses without arresting the action of the profile-cutters.

50 The heel of the cutter *b* forms virtually a stop for the work for gaging the depth of cut, and as these cutters are worn away by sharpening the point of support for the work on the back of the cutters will shift rearward in exact proportion to the relative recession 55 of the cutting-edge from the heel of the next adjacent cutter.

A convenient mode of making the cutters *b*

is to take a ring of steel of suitable breadth and thickness and to turn up its outer periphery to correspond to the profile of the edge-paring to be effected, and then to cut up the ring into sections and to reduce the breadth of these sections by filing, so as to obtain the requisite spaces between the cutters for the traverse of the blades of the cutter *D* as well 70 as the discharge of the chips of leather.

The holder *B*, to which the segment-shaped cutters are fitted, has a diameter corresponding to the internal diameter of the ring from which the cutters are formed, and the seats 80 for the cutters are made by planing down the periphery eccentrically, as shown in the detached view, Fig. 5.

From the foregoing description it will be readily understood how the edge paring and 85 chamfering of the soles of boots and shoes may be simultaneously and accurately effected by the use of this compound cutter.

The several sets of cutting-edges having been properly adjusted relatively to each 90 other to suit the work in hand, the boot is held up to the cutter, as indicated in Fig. 1, the edge of the steel ring *E* being entered into the crease of the boot. Rotary motion having been imparted to the cutter, the edge of the 95 sole will be acted upon by the profile-cutters *b* and the face of the sole near the edge by the chamfering-cutter *D*, while the burr at the upper edge of the sole is removed by the biting-cutter *E*. The chips made by the action 100 of these several cutters will fall through the spaces between the profile-blades and will be drawn through the conical guard *F*, the inclined arms of that guard acting as an exhaust-fan to draw away the dust and chips of 105 leather as they fall into the space between the cutter-holder *B* and the guard *F*.

The modified form of profile-cutter illustrated at Figs. 10 and 11 shows that the cutters, instead of forming portions of a ring, 110 may be made with a face straight from edge to heel. This will lessen the amount of contact between the cutters and the work, and thereby reduce the tendency of the cutters to heat. An incidental advantage of this modification is that the number of blades may be increased. Thus the figures show twelve 115 blades in place of the six in Figs. 1 and 2.

Having now particularly described and ascertained the nature of our said invention 120 and in what manner the same is to be performed, we declare that what we claim is—

1. The combination, in a compound cutter for paring boot or shoe soles, of a profile-cutter holder fitted with spaced blades, a 125 chamfering-cutter holder, a chamfering-cutter carried thereby, the blades of which are capable of sliding between the spaced blades of the profile-cutter, a biting-cutter, a holder to which said biting-cutter is secured and 130 which acts as a guide, a sleeve to which the chamfering-cutter is connected adjustably, said sleeve fitting and being capable of sliding upon the profile-cutter for the purpose of ad-

justing the chamfering-cutter to the profile-cutter to suit the work in hand, and a spindle to which the profile-cutter is secured and upon which the bitting-cutter holder is frictionally held, all the said cutters being rotated by the said spindle, substantially as and for the purpose above set forth.

2. The combination, in a compound cutter for paring boot or shoe soles, of a profile-cutter holder fitted with spaced blades, a chamfering-cutter holder, a chamfering-cutter carried thereby, the blades of which are capable of sliding between the spaced blades of the profile-cutter, a bitting-cutter, a hollow exhaust-holder to which said bitting-cutter is secured and which acts as a guide, a sleeve to which the chamfering-cutter is connected adjustably, said sleeve fitting and being capable of sliding upon the profile-cutter for the purpose of adjusting the chamfering-cutter to the profile-cutter to suit the work in hand, and a spindle to which the profile-cutter is

secured and upon which the bitting-cutter holder is frictionally held, all the said cutters being rotated by the said spindle, substantially as and for the purpose above set forth. 25

3. In compound rotary cutters for boot or shoe paring machines, the combination of the chamfering-cutter holder C, the cutter D secured thereto, an adjustable sleeve A', in which the cutter-holder C is supported, the sleeve A' having radial recesses a to receive the blades of the cutter D, means for adjusting the said cutter-holder relatively to the sleeve, and a rotary spindle to actuate the parts, substantially as herein described. 30 35
